DESIGN FOR A SETTEE

Bernard Sky, Toronto, Ontario, Canada, assignor
to Skyline Moulded Furniture Company Limited,
Toronto, Ontario, Canada

Application October 27, 1945, Serial No. 123,237
In Canada July 5, 1945

Term of patent 14 years

(Cl. D15—11)

To all whom it may concern:

Be it known that I, Bernard Sky, a citizen of Canada, residing in the city of Toronto, county of York, Province of Ontario, and Dominion of Canada, have invented a new, original, and ornamental Design for Settees, of which the following is a specification, reference being had to the accompanying drawings, forming part thereof.

Fig. 1 is a view in perspective of a settee showing the new design.

Fig. 2 is a side elevational view; and
Fig. 3 a top plan view thereof.

I claim:

The ornamental design for a settee, as shown.

BERNARD SKY.
